UNITED STATES PATENT OFFICE.

GEORGE W. LANCASTER, OF RICHMOND, VIRGINIA, ASSIGNOR TO PERFECTED WINDOW COMPANY, (INCORPORATED,) OF RICHMOND, VIRGINIA.

INTERLOCKING SWINGING SASH AND CASEMENT AND LOCK THEREFOR.

1,416,097.

Specification of Letters Patent. Patented May 16, 1922.

Application filed January 5, 1921. Serial No. 435,234.

To all whom it may concern:

Be it known that GEORGE W. LANCASTER, a citizen of the United States of America, residing at Richmond, county of Henrico, 5 and State of Virginia, has invented a new and useful Interlocking Swinging Sash and Casement and Lock Therefor, of which the following is a specification.

The invention has for its purpose the provision of an interlocking swinging sash and casement and lock therefor, wherein a plurality of counterbalancing auxiliary sashes are employed, and another purpose is to provide a construction, which is simple, and 15 practical in construction.

In a copending application in the name of George W. Lancaster filed February 20, 1920, Serial No. 360,151, a swinging sash and casement are employed. In such construction, as a result of practical installation, it has been found that the swinging sash does 20 not close tight enough in order to preclude all the air or wind.

Furthermore in a construction as embodied in said application, the locking means for the swinging sash is not as secure, as has been found necessary. For instance an operator is very apt not to move the locking means its fullest extent for the purpose of 25 locking the swinging sash. Furthermore when the locking means is moved to an operated position and the sash swung open, the operator, when again closing the sash may find the locking means in a locked position 30 with the swinging sash in an opened position, therefore when the operator attempts to again close the sash, the combination locking means and weather strip is very apt to contact with the sill of the casement, 35 thereby not only preventing the swinging sash from being closed, but distorting the combination locking means and weather strip, at a point adjacent the hinge of the sash.

Therefore, still another purpose is to provide a construction of interlocking swinging sash and casement and lock therefor, whereby the above disadvantages are overcome.

For example, it is a further purpose to provide a swinging sash having interlocking 50 flange connections with the casement, in such a manner as to preclude the air and wind entering the room at the joint between the swinging sash and the casement.

A still further purpose is to provide means

for locking the combined locking device and 55 weather strip in locked or unlocked position relatively to the casement, so that when an operator closes the swinging sash, it will be found necessary to unlock the locking means from its unlocked position, in order to insure 60 that the operator will lock the swinging sash, after it is completely closed, thereby preventing the combined locking member and weather strip from abutting with the sill, which will distort said weather strip, 65 and when the swinging sash is opened, the combined locking member and weather strip may be locked in an unlocked position. By an arrangement of this kind the operator is assured 70 that the combined locking member and weather strip is locked in a locked position, when the swinging sash is closed.

While the design and construction at present illustrated and set forth is deemed preferable, it is obvious that as a result of a reduction 75 of the invention to a more practical form for commercial purposes, the invention may be susceptible of changes, and the right to these changes is claimed, provided they are comprehended within the scope of what 80 is claimed.

The invention comprises further features and combination of parts, as will be herein-after set forth, shown in the drawings and 85 claimed.

In the drawings:—

Figure 1 is a vertical sectional view through a window, wherein a casement is employed as the window frame showing a swinging sash containing a plurality of auxiliary counterbalancing sashes, with means for adjusting one of the sashes, relatively to 90 slides.

Figure 2 is a view in elevation of the swinging sash, showing the combination locking member and weather strip as applied.

Figure 3 is a horizontal sectional view on line 3—3 of Figure 1, showing the interlocking connections between the swinging sash 100 and casement, and also illustrating the combined locking member and weather strip, with means for locking the strip in locked or unlocked positions.

Figure 4 is an enlarged detail view in elevation of the lower right hand corner of the swinging sash shown in Figure 2, with the sash in section, showing the locking

weather strip moved to an unlocked position and the means for holding it in such position.

Figure 5 is an edge elevation of Figure 4. Referring to the drawings, 1 designates a wall of a building having an opening 2, in which the window frame or casement 3 is mounted. This casement may be any suitable shape preferably angular in cross section as shown, and the inner and lower walls thereof having lateral flanges 4 which are engaged in the wall, to hold the window frame or casement in place. This casement may be made up in any manner found convenient, preferably in the manner as disclosed in said copending application. For instance the casement or window frame may be made in sections, and the sections spot welded (not shown). The casement or window frame has a shoulder 5 at the top, and shoulders 6 and 7 at the sides. Shoulders of this character are eliminated at the sill of the frame or casement, with the exception of a shoulder 8 facing outwardly. The casement at the top and bottom and at one side is bent or constructed to provide a channel 9, while the other side of the casement or frame has a rabbet 10.

A dominant window sash 11 engages the opening in the frame or casement, and is hingedly mounted on the casement as at 12, whereby the dominant sash may swing inwardly of the room. The shoulders 6 and 7 at the opposite sides of the casement or window frame constitute walls of opposite channels 13 and 14. The side of the casement or window frame adjacent the hinge side of the dominant sash is provided with a vertical channel 15 between the rabbet 10 and the channel 13.

The window frame or casement may be constructed of any suitable sheet metal preferably steel or any gauge found convenient for the purpose, while the dominant sash 45 may be constructed of similar material. This dominant sash may consist of side, top and bottom rails, which may be put together by spot welding in a manner similar to the construction of the casement or window frame, as disclosed in said copending application.

The dominant sash is rectangular in cross section, and it will be noted that the outer wall 16 of the dominant swinging sash on three of its sides, namely the top, bottom and the free side terminates in a marginal flange 17, which engages the channel 9, which is formed in the inner wall of the casement or window frame at its top and bottom and one of its sides, so that when the dominant sash is closed, the flange 17 will fit tight and preclude the air or wind from entering the room.

The hinge side of the dominant sash between the inner and outer walls is provided

with a vertical angle strip 18, which is fastened, preferably by spot welding to the wall of the swinging dominant sash, and is designed to enter the channel 15 when the dominant swinging sash is closed, thereby assisting materially with the interengagement of the outer wall of the dominant swinging sash with the channel 13, to preclude the air or wind.

In order to insure holding the dominant swinging sash closed, and also to assist in precluding the air or wind, a combined locking member and weather strip 19 is mounted adjacent the outer wall of the dominant sash at the bottom and one side thereof. This combined locking member and weather strip is in the form of a right angle, and is provided with arcuate slots 20, which are engaged by the guide pins 21, so as to mount the strip and guide the same for the purpose intended. When the swinging dominant sash is closed, it is the aim to move this combined locking member and weather strip, for the purpose of locking the sash, and at the same time to assist materially in precluding the weather. In order to accomplish this the vertical arm of the right angle weather strip engages the channel 14 against the shoulder 22, whereas the lower horizontal arm 23 engages the shoulder 8, which is slightly inclined downwardly and outwardly, so that the arm 23 will cam thereon and draw the dominant sash in position tightly. In other words by this means the lower part of the flange 17 will be drawn tightly into the lower part of the channel 9. The interengagement of the lower arm 23 of the right angle weather strip will also tend to draw the vertical free portion of the dominant sash closely in position in engagement with the jamb of the window frame or casement.

In order to hold the combined locking member and weather strip in a locked position, a pin 24 is mounted in a guide opening 25 of the inner wall of the dominant swinging sash. The pin 24 is also mounted in the guide opening 26 of a bracket arm 27, which is fastened to the inner surface of the dominant swinging sash in any suitable manner preferably by spot welding as indicated at 28. A coiled expansion spring 29 is in surrounding relation to the pin 24 and is interposed between a shoulder 30 and the wall of the sash. It will be noted that the action of the spring holds the end 31 of the pin in contact with the inner surface of the outer wall of the dominant sash normally. The pin 24 has a head 32, which is positioned adjacent the inner wall of the dominant sash. When the combined locking member and weather strip is in a locked position, as shown in Figure 2, the end of the pin 24 engages one edge of the right angle locking member and weather strip and holds the vertical arm 130

thereof in the channel 14, the wall 22 of which is inclined or bevelled, so that the weather strip may cam thereon and draw the window sash tightly in place. When the 5 combined locking member and weather strip is unlocked, the end 31 of the pin 24 may engage the opposite edge of the vertical arm of the weather strip, as shown in Figure 4, so as to hold the weather strip in an 10 unlocked position, thereby preventing the weather strip from contacting with the front 8 of the sill when the operator is attempting to close the sash.

The combined locking member and weather 15 strip has pivoted thereto, as at 34, an arm 35, and which is mounted on a rotating pin 36, which is mounted in bearings 37 of the inner and outer walls of the dominant swinging sash. The inner end of the pin 36 has a 20 transverse pin, by which the pin 36 may be rotated. It is obvious that owing to the arm 35 and its connection with the strip, the pin will impart movement to the combined locking member and weather strip, in order to 25 move it to locked or unlocked position. It will be noted that the locking pin 24 is directly under the pin 36, though it is obvious that it may be above. By means of this construction, it is assured that an operator will 30 not be very apt to jam the lower horizontal arm of the weather strip against the inner lower portion of the casing.

The opposing walls of the dominant sash have mounted thereon channel guides 38, 35 which are in sections 39 and 40, the sections 39 constituting the upper stationary parts of the channel guides, while the sections 40 constitute the lower removable channel guides. It will be noted that these guides are mounted 40 on opposite sides of the sash, though only one side is shown in Figure 1, whereas in Figure 2 the opposite sides are shown. The lower sections of channel guides are removable, due to the fact that they are secured in 45 place by means of the screws 41, which pass through the walls of the sash and are threaded into the heavy metallic strips 42, which are secured in any suitable manner preferably by spot welding, to the inner surface 50 of the opposite walls of the sash. These heavy metallic strips are provided for the purpose of insuring a backing for the screws, since if the screws were simply threaded through the sheet metal there 55 would not be sufficient gripping surface for the threads of the screws. The joint between the upper and lower sections of channel guides is indicated at 43. By rendering the lower sections of channel guides removable, it is possible to remove the auxiliary 60 sashes. Mounted in the channel guides 38 are upper outermost and lowermost inner and intermediate auxiliary sashes provided with interlocking flanges 44, which act to 65 preclude the air or wind from entering the

interior of the room. The upper outermost auxiliary sash 44^a when in its normal position engages the transverse bar or strip 45, in order to assist in precluding the air or wind.

70

Engaging two of the channel guides 39, namely those nearest the interior of the room and reaching over the intermediate walls between such two channel guides, are

75

slides 46 having channels 47, in which the lower innermost auxiliary sash is mounted and guided. The intermediate channel of each slide which straddles the adjacent flanges of the channel guides has one of its walls provided with arms or lugs 48. The

80

upper arm or lug 48 is longer than the lower arms or lugs 48, and preferably fits the space between one wall of the slides and the opposite wall of the innermost channel guide.

85

A transverse bar 49 is designed to engage under any two opposite lugs or arms 48, for the purpose of raising the slides, and when raising the slides to raise the lower innermost auxiliary sash. Mounted in bearings

90

on the interior of the upper part of the dominant sash are pulleys 50 and 51. Passing over the pulleys 50 is a sash cord 52, which is connected at 53 to the outer uppermost auxiliary sash, and is in turn connected to the transverse bar 49. It will be noted

95

that when the upper outermost sash is lowered, the bar 49 is raised, and when raised, the inner lowermost auxiliary sash may or may not be raised, it depending entirely upon whether the slide is moved or not.

100

Passing over the pulley 51 is a sash cord 54, which has its opposite ends connected at 55 to the upper parts of the intermediate auxiliary sashes 55^a and 55^b. The intermediate

105

sashes counterbalance each other, it being obvious that should the lower intermediate sash be raised, the upper intermediate sash is lowered and vice versa. The opposite slides 46 have their lower ends connected by means of a transverse bar 56, with which the lower

110

portion of the lower innermost auxiliary sash 44^b engages, in order to preclude the air or wind. The lower ends of the channels 47 of the opposite slides are closed by means of the end pieces 57, so that when the slides are

115

raised, the lower innermost auxiliary sash may be likewise raised, similar to the idea disclosed in the copending application filed the 5th day of January, 1921, in the name of George W. Lancaster, Serial No. 435,233.

120

The sash cords or tables may be constructed of any suitable material, either rope, chain, or suitable metallic cable material, or in fact any material, which will not necessarily bind or buckle. Furthermore

125

suitable lubricant or graphite may be applied to the sash cords or cables, or chains, or upon the pulleys engaged by the cords, or if desired the cords, chains or the like may pass through holders (not shown), which

130

may contain the lubricant or graphite or other material.

While the drawings show the glasses clamped in the channels of the auxiliary sashes, with the metal of the material in direct contact with the glasses, it is obvious that any suitable material may be used in the channels of the sashes, so that the glasses may fit closely and tightly therein, and in such a manner as to preclude the air or wind. In constructing these sashes with the glasses therein, putty or similar material has been used, and while there has been considerable success with this kind of material, considerable success and advantages have been attained by the use of asbestos, either in a pliable moist state, or in a dry form. In fact any form of asbestos has been found more preferable in joints, in order to preclude the air or wind. Furthermore such material is very essential due to its fire proof properties. Asbestos in any form is not only preferable in the channels of the auxiliary sashes for the glasses, but may also be used between the overlapping joints 44, as well as in the channels 9, and any similar parts. In fact asbestos may be used where the casement engages in the wall, as at 4.

Also it is to be noted that the casement and the channels carried by the opposite sides of the swinging dominant sash may be constructed in any suitable manner, preferably by a rolling process. In fact the channels constituting guides for the auxiliary sashes may be constructed from sheet metal, rolled from one piece in order to form the guides. Also the dominant swinging sash may be constructed of rolled sheet material.

The invention having been set forth, what is claimed is:—

1. In a window construction, a window casement, a swinging closure hingedly mounted therein, the wall of the casement having channels, the inner wall of the swinging closure having marginal flanges to engage said channels, and means for locking the closure and drawing the marginal flanges into interlocking engagement with the channel to insure precluding the air or wind.

2. In a window construction, a window casement, a swinging closure hingedly mounted therein, the wall of the casement having channels, the inner wall of the swinging closure having marginal flanges to engage said channels, and means for locking the closure and drawing the marginal flanges into interlocking engagement with the channel to insure precluding the air or wind, and means for locking the locking means in locked or unlocked position.

3. In a window construction, a window casement having channels adjacent its inner and outer portions, a closure hingedly mounted in the opening of the casement and

having marginal flanges to interlock in said channels, a combined locking member and weather strip carried by the closure and having a locking and camming engagement with certain of the inner channels for drawing the closure into an interlocked tight engagement with the casement, and manual means for moving the weather strip to a locked or unlocked position.

4. In a window construction, a window casement having channels adjacent its inner and outer portions, a closure hingedly mounted in the opening of the casement and having marginal flanges to interlock in said channels, a combined locking member and weather strip carried by the closure and having a locking and camming engagement with certain of the inner channels for drawing the closure into an interlocked tight engagement with the casement, and manual means for moving the weather strip to a locked or unlocked position, said means comprising an opening formed in one arm of the weather strip, a rotating rod mounted in bearings of the closure, and a cam carried by the rod engaging said opening for moving the weather strip to a locked or unlocked position.

5. In a window construction, a window casement having channels adjacent its inner and outer portions, a closure hingedly mounted in the opening of the casement and having marginal flanges to interlock in said channels, a combined locking member and weather strip carried by the closure and having a locking and camming engagement with certain of the inner channels for drawing the closure into an interlocked tight engagement with the casement, and manual means for moving the weather strip to a locked or unlocked position, and means for locking the weather strip in locked or unlocked position.

6. In a window construction, a window casement having channels adjacent its inner and outer portions, a closure hingedly mounted in the opening of the casement and having marginal flanges to interlock in said channels, a combined locking member and weather strip carried by the closure and having a locking and camming engagement with certain of the inner channels for drawing the closure into an interlocked tight engagement with the casement, and manual means for moving the weather strip to a locked or unlocked position, said means comprising an arm connected to one arm of the weather strip, a rotating rod mounted in bearings of the closure and carrying said arm for moving the weather strip to a locked or unlocked position, and means for locking the weather strip in locked or unlocked position.

7. In a window construction, a window casement having channels adjacent its in-

- ner and outer portions, a closure hingedly mounted in the opening of the casement and having marginal flanges to interlock in said channels, a combined locking member and 5 weather strip carried by the closure and having a locking and camming engagement with certain of the inner channels for drawing the closure into an interlocked tight engagement with the casement, and manual 10 means for moving the weather strip to a locked or unlocked position, and means for locking the weather strip in locked or unlocked position, said last mentioned means comprising a reciprocating detent member mounted 15 in bearings of the sash, tensioning means for said detent member to hold the detent member in engagement with either of its opposite edges of the weather strip to hold it in locked or unlocked position.
8. In a window construction, a window 20 casement, a swinging closure hingedly mounted therein and provided with a locking weather strip, the wall of the casement having a keeper channel to receive said weather strip when the closure is closed, 25 means for moving the weather strip into and out of locked position, and means adapted to assume a position in the path of the weather strip whether in a locked or unlocked position, to hold it in either of its 30 positions.

In witness whereof, in the presence of two witnesses, the inventor's signature is hereunto affixed.

GEORGE W. LANCASTER.
